UNITED STATES PATENT OFFICE

167,572

COMBINED TOBACCO POUCH AND LIGHTER

Robert P. Huesman, South Fort Mitchell, Ky.

Application May 9, 1950, Serial No. 9,838

Term of patent 14 years

(Cl. D85—2)

To all whom it may concern:

Be it known that I, Robert P. Huesman, a citizen of the United States, residing at South Fort Mitchell, in the county of Kenton, and State of Kentucky, have invented a new, original, and ornamental Design for a Combined Tobacco Pouch and Lighter, of which the following is a specification, reference being had to the accompanying drawing, forming part thereof.

Fig. 1 is a perspective view of a combined tobacco pouch and lighter, showing my new design, that side of the article not shown has substantially the same appearance as the side shown in Fig. 1.

Fig. 2 is a top plan view of the device of Fig. 1.

I claim:

The ornamental design for a combined tobacco pouch and lighter, as shown and described.

ROBERT P. HUESMAN.
